UNITED STATES PATENT OFFICE.

WALTER W. REED, OF ROCKLAND, MASSACHUSETTS.

MEANS FOR STEAMING BOX-TOES.

1,187,651.

Specification of Letters Patent. Patented June 20, 1916.

Application filed July 9, 1915. Serial No. 38,968.

To all whom it may concern:

Be it known that I, WALTER W. REED, a citizen of the United States, residing at Rockland, in the county of Plymouth, in the State of Massachusetts, have invented a certain new and useful Improvement in Means for Steaming Box-Toes, of which the following is a specification, reference being had to the accompanying drawings.

10 In the manufacture of shoes, and the like footwear, in the operation of conforming the leather toe blank from the flat to the box shape, it is the common practice to steam the said blank in order to soften it to some extent, and then to pull the said blank over the last and tack the edge portions of the blank in order to retain the same in its conformed condition. In thus steaming the blank the finished outer surface of the 20 leather is softened and dulled objectionably, and it frequently becomes necessary to re-finish the said outer surface after the shoe is otherwise complete.

25 In my new method of and means for forming the box toe blank, the finished surface of the leather is not required to be steamed and softened yet the operation is performed as expeditiously and cheaply as by the methods now in use.

30 In order to explain my invention clearly I have provided the annexed drawings, in which—

Figure 1 is a perspective view of a hot water, or steam distributing system whereby 35 a plurality of pulling over, and toe-steaming devices of my present improved type, may be conveniently operated. Fig. 2 is a side elevation of the toe steaming device which forms the chief feature of the present invention, and Fig. 3 is a central, vertical, sectional view of the same. Fig. 4 is a transverse sectional view of the said toe-steaming device taken at the line 4—4 of Fig. 3. Fig. 5 is a perspective view of the 45 discharge throat of said steaming device. In Fig. 6 I have shown an elevation of the steaming device having mounted thereon a shoe support, with a shoe in proper position for the steaming of the box-toe blank and 50 in Fig. 7 the upper end portion of the steaming device is illustrated in vertical section. Fig. 8 is a perspective view of a steam-box by means of which the under side of the box toe blank may receive a preliminary softening before it is mounted on the last and pulled over at its side portions.

My present invention relates more particularly to the novel device for steaming the under side of the box toe blank after the sides of the latter have been pulled over and tacked but, in order to explain said present improvement understandingly, I have illustrated a novel system of which the said steaming device is a feature.

In the Fig. 1 the numeral 20 indicates a main distributing pipe leading from a steam, or hot water, tank 21, the pipe 20 being provided with a plurality of branch pipes, here shown as four in number and indicated by the numerals 22, 23, 24 and 25. Any desired number of branch pipes may however, be provided, it being my intention to mount upon certain of the said branch pipes several of the steam boxes shown in Fig. 8, and upon certain other branch pipes 75 my special form of toe steaming devices; the steam boxes being located preferably adjacent to pulling-over machines.

As stated above, the toe blanks may be first softened to some extent by placing them 80 in steam boxes such as the box 26 shown in Fig. 8 of the drawings and which I will describe more specifically hereinafter. The toe blank is then placed in position on the last and is pulled over and tacked down at 85 its side portions. The shoe is then placed on a support, of the type shown at 27 in Fig. 6, the free front edge portion of the toe blank being then so positioned that it is immediately over the curved throat 90 portion 28; the arrangement of throat and toe blank being such that a jet of steam or vapor discharged from said throat will impinge against the under side of the said blank and soften the same at precisely the 95 point or part which must be pulled over to form the curved front portion of the box. The blank is thus steamed and rendered sufficiently pliable without unduly steaming the outer, finished, surface of the leather. 100

My said steaming device consists essentially of a cylindrical body portion 29, which is mounted on one of the branch pipes 24 or 25, and a removable top section 30 which terminates in the curved throat 28 105 already referred to. The top section 30 is planned to fit into the upper end of the body portion 29 and is formed with a radial projection 30^a which is adapted to interlock with a correspondingly shaped socket 29^a 110 in the body 29 thus providing a "bayonet" lock-joint whereby the top section 30 may

be readily attached to or removed from the body section. In the event that water is introduced into the body 29, through the branch pipe, instead of steam, the water 5 may be heated to the desired degree by means of an electrically heated resistance coil located in a central chamber 31 in the lower portion of the body 29 but as such resistance coil forms no part of my present 10 invention I have considered it unnecessary to illustrate it.

By preference the extreme opposite end portions of the throat 28 are slightly enlarged and flared, as seen at 28^a in Fig. 5 15 of the drawings, so that a part of the steam, as it leaves the throat, will be discharged along the inner sides of the toe blank as well as the curved front end portion of said blank. The shoe support 27 is supported 20 on an arm 32 whose lower end portion fits loosely in a socket 33 formed in a web 34 which is integral with the body 29 as here illustrated, the arrangement being such that the toe portion of the shoe may be swung 25 into or out of register with the throat 28.

The preliminary steam box 26 may, or may not be used. It includes a housing whose bottom is adapted to receive the discharge of steam or water, as the case may 30 be, from the branch pipe upon which the housing is mounted. Within the said hous-

ing is a grid 35 upon which the box toe blanks may be laid for steaming and adjacent to the said grid are slotted openings 36 through which the blanks may be inserted and removed. By preference the housing is provided at its upper portion with an opening 37 through which the steam or vapor may escape as it passes upward from the grid. 40

My described toe steaming device is of such construction that it may be conveniently used and it effectually overcomes, or rather renders unnecessary, the objectionable softening and defacing of the finished outer 45 surface of the toe cap which results from the present system of box toe making.

Having thus described my invention, I claim as new and wish to secure by Letters Patent:— 50

A box-toe steaming device, including a throat portion constructed and arranged to fit the toe portion of a shoe and having a discharge opening with its walls curved inwardly at their forward edges along parallel arcuate lines, said walls being laterally flared at the ends to provide for the delivery of the steam or vapor leaving the throat portion along the inner sides of the toe blank and the curved front end portion of 60 said toe blank.

WALTER W. REED.

Copies of this patent may be obtained for five cents each, by addressing the "Commissioner of Patents, Washington, D. C."
